UNITED STATES PATENT OFFICE.

CHARLES F. GAUNT, OF BIRMINGHAM, ENGLAND.

DESIGN FOR AN ASH TRAY.

Application filed October 5, 1922. Serial No. 3,885. Term of patent 14 years.

To all whom it may concern:

Be it known that I, CHARLES F. GAUNT, a subject of the King of Great Britain, and resident of the city of Birmingham, England, have invented a new, original, and ornamental Design for Ash Tray, of which the following is a specification, reference being had to the accompanying drawing, forming a part thereof.

I claim—

The ornamental design for an ash tray as shown.

Signed at the city of Montreal, this eighteenth day of September, 1922.

CHARLES F. GAUNT.

In presence of—

GORDON G. COOKE,
HARRIETTE McDONALD.
